US00D917705S

(12) **United States Design Patent** (10) **Patent No.:** **US D917,705 S**
(45) **Date of Patent:** **** Apr. 27, 2021**

(54) **BODY COMPOSITION MEASURING APPARATUS**

(71) Applicant: **Socionext Inc.**, Kanagawa (JP)

(72) Inventors: **Ryusuke Kurachi**, Kanagawa (JP);
Mari Kobayashi, Kanagawa (JP);
Kazuyuki Kanazashi, Kanagawa (JP)

(73) Assignee: **Socionext Inc.**, Kanagawa (JP)

(**) Term: **15 Years**

(21) Appl. No.: **29/646,292**

(22) Filed: **May 3, 2018**

Related U.S. Application Data

(62) Division of application No. 35/502,796, filed on Oct. 12, 2016 (U.S. filing date under 35 U.S.C. 384), and having an international filing date of Oct. 12, 2016, now Pat. No. Des. 861,179.

(57) **CLAIM**

The ornamental design for a body composition measuring apparatus therefor, as shown and described.

DESCRIPTION

FIG. 1: Perspective View of the body composition measuring apparatus.

FIG. 2: Front View thereof.

FIG. 3: Back View thereof.

FIG. 4: Right View thereof.

FIG. 5: Left View thereof.

FIG. 6: Top View thereof; and,

FIG. 7: Bottom View thereof.

The broken lines shown in at least FIG. 3 illustrate environmental subject matter and/or elements that form no part of the claimed design.

1 Claim, 7 Drawing Sheets
